(57) **CLAIM**

The ornamental design for a faucet, as shown and described.

DESCRIPTION

FIG. 1 shows a top perspective view of the faucet.

FIG. 2 shows a front elevation view thereof.

FIG. 3 shows a left-side elevation view thereof.

FIG. 4 shows a back elevation view thereof.

FIG. 5 shows a right-side elevation view thereof; and,
FIG. 6 shows a top plan view thereof.

The broken lines (regular dashes) shown in the figures depict portions of the faucet that form no part of the claimed design. The dot-dash lines represent imaginary lines not part of the actual article structure to identify boundaries of the claim when there is no natural boundary to do so.
